Application February 13, 1943, Serial No. 475,729

27 Claims. (Cl. 235—82)

1

This invention relates to calculating machines of the type in which items of a calculation are set up in succession by selective operation of keys of a keyboard, and the items entered in a totalizer or accumulator in the performance of a calculation.

An object of the invention is to provide an improved calculating machine with which different types of calculations may be made in an exceptionally simple manner, by simple adjustments and with simple mechanism, which will be compact, sturdy, capable of rapid operation, and inexpensive.

Another object of the invention is to provide an improved calculating machine which will perform selectively either addition or subtraction, which will require a minimum of parts, with which adjustment to perform either subtraction or addition selectively may be made quickly by a simple operation, which may be made of any desired capacity, which will utilize a minimum number of parts, with which repeat entries of any number set up in the keyboard, whether of subtraction or addition, may be made any number of times, by operation of a repeat control, with which the totalizer may be cleared in a simple and rapid manner, which at the end of a subtraction operation, when the machine is not set for repeat, will automatically reset the machine for addition, with which such resetting means will be incapacitated by operation of the repeat control, and which will be exceptionally simple, compact, inexpensive and dependable.

Another object of the invention is to provide an improved, simplified, compact, and readily portable calculating machine which will selectively perform either addition or subtraction, and which will have maximum possible control against the performance of incorrect operations that might cause an error in the calculations.

Other objects and advantages will be apparent from the following description of one embodiment of the invention, and the novel features will be particularly pointed out hereinafter in connection with the appended claims.

In the accompanying drawings:

Fig. 1 is a top plan view on a reduced scale, partly broken away, of a machine embodying the invention and showing the parts in normal position;

Fig. 2 is a fragmentary similar view in which the keyboard has been shifted to subtraction position;

Fig. 3 is a fragmentary plan of the same, showing the means for slidably supporting the rear

2

of the keyboard, the parts being in normal position;

Fig. 4 is a similar view showing the means for supporting the front part of the keyboard;

5 Figs. 5 and 6 are views similar to Figs. 3 and 4, and showing the keyboard shifted to and latched in subtraction position;

Fig. 7 is a side elevation of the machine, with the parts in normal position and a portion of the 10 cover shown in section;

Fig. 8 is a fragmentary similar view, showing the position that the parts assume in a partial forward stroke;

Fig. 9 is a fragmentary sectional plan view 15 of the machine, the section being taken approximately along the line 9—9 of Fig. 7;

Figs. 9a, 9b and 9c are fragmentary sectional elevations of parts of the totalizer with the parts in different possible operative positions;

20 Fig. 10 is a fragmentary longitudinal section of the machine, the section being taken approximately on the line 10—10, Fig. 18;

Fig. 11 is a fragmentary sectional elevation 25 showing the pair of stop bars of the units denominated column in normal position;

Fig. 12 is a similar view showing a pair of stop bars for the 10's or higher denominational columns;

Fig. 13 is a front elevation of the keyboard and 30 associated parts of the machine in position for addition and having one of the keys of the keyboard depressed;

Fig. 14 is a similar view, partly in section, but 35 illustrating the keyboard shifted to subtraction position;

Figs. 15 and 16 are fragmentary, transverse, 40 sectional elevations of portions of the keyboard, with the sections taken approximately along line 15—15 of Fig. 12, and showing the same parts with the keyboard in addition and subtraction positions respectively;

Fig. 17 is a longitudinal, sectional elevation 45 through the machine, the section being taken approximately in the plane represented by the line 17—17 of Fig. 9;

Fig. 18 is a fragmentary transverse section of the machine, the section being taken approximately on the line 18—18 of Fig. 10;

Fig. 19 is a fragmentary side elevation of certain 50 parts of the machine shown in Fig. 7, illustrating the position that these parts occupy at the end of a forward stroke;

Fig. 20 is a fragmentary side elevation, partly 55 in section, showing the position of certain parts when set for clearing the machine;

Fig. 21 is a fragmentary, transverse section of part of the machine, the section being taken approximately on the line 21—21 of Fig. 20;

Fig. 22 is a view similar to Fig. 20 and illustrating the position that the parts assume just after the beginning of a return stroke;

Fig. 23 is another similar view illustrating in full lines the means for releasing the accumulator at a subsequent instant in the clearance stroke and illustrating in broken lines the parts of the clearance mechanism returning to normal position;

Fig. 24 is a fragmentary, longitudinal, sectional elevation of parts of the machine, illustrating the position of the 10's denominational stop bars just before the completion of a blank forward stroke, the parts being set for subtraction;

Fig. 25 is a similar view showing these parts at the completion of a blank forward stroke, the parts being set for subtraction;

Fig. 26 is a fragmentary sectional plan view of a part of the machine, the section being taken approximately on the line 26—26 of Fig. 25;

Fig. 27 is a fragmentary longitudinal sectional elevation of part of the machine, showing the front portions of a pair of 10's or higher denominational stop bars when the machine is set for subtraction and a key is depressed; and

Fig. 28 is a similar view, but illustrating a partial forward movement of the stop bars shown in Fig. 27.

The particular illustrated embodiment of the invention is an addition and subtraction machine of the general type disclosed in United States patents to Peters No. 1,386,021, of August 2, 1921, and White No. 1,854,875, of April 19, 1932, and my copending application Serial No. 416,833, filed October 28, 1941, now patent No. 2,428,084, and this invention is in the nature of an improvement upon the type of calculating machines disclosed in said application and said White and Peters patents.

In this illustrated embodiment of the invention, the operating parts are mounted in a frame 1, Figs. 7 and 9, which is similar in character to the usual frame of calculating machines with a base and upstanding side members 2 and 3 of rigid material, such as heavy metal plates. Extending between and through the side members 2 and 3 is a main shaft 4 which is suitably mounted for rocking oscillation in the side members 2 and 3, and one end of the shaft is formed to receive removably thereon an operating handle 5, as usual in hand-operated calculating machines. It will be understood, however, that an operating handle has been disclosed as the motive means for the main shaft 4 because of its simplicity, but motor operated means for the main shaft 4 may be provided as disclosed in my said copending application Serial No. 416,833. Inasmuch as the manner in which the shaft 4 is operated in an oscillating or rocking manner, is not material to the invention sought to be covered in this application, the motor operated means for operating the driving shaft 4 in a given cycle of movement has been omitted, and the simple handle 5 is illustrated merely by way of example.

The main shaft 4 is provided with an arm 6 (Fig. 17) fixed thereon, and a free end of this arm is connected to one end of a coil spring 7, the other end of which is anchored in any suitable manner with the spring under tension, such as by a stud 8 on the base of the frame 1. This

spring 7 yieldingly urges the shaft 4 back into an initial position which is determined by the engagement of a heel 9, Fig. 7, with a buffer element 10 which is supported at one end on the shank of a headed stud 11, and at its other end is forked to straddle a horizontally extending lug or shelf 12 provided on the side member 3 of the frame. One arm 13 of the forked end of the member 10 extends above the lug 12, and a helical compression spring 14 is disposed between this arm 13 and the upper face of the lug 12. The arm 13 is also provided with a small lug 15, extending toward the other arm of the fork, which engages in a notch or slot 16 in the end of the lug 12, so that as the arm 13 moves vertically, the lug 15, by vertical sliding engagement in the slot 16, will prevent sidewise movement of the adjacent end of arm 13. The heel 9 is provided on a full stroke sector plate 17 which is fixed on the shaft 4 for oscillation therewith, and the heel 9 engages the member 10 in close proximity to the stud 11, so as to provide a substantially non-yielding limit stop for the full stroke sector and the shaft 4.

The sector 17 (Figs. 7, 20 and 22) is provided with the usual ratchet notches 18 in a zone of its periphery for engagement by a full stroke pawl 19 pivoted on a stud 20 on the side member 3 of the frame. A spring 21 connected to the pawl 19 urges it into a dead center position, and the notched edge of the sector 17 is provided adjacent its ends with deeper notches 22, which moves opposite the pawl 19 at the limits of the movement of the shaft 4 and the sector plate 17, so that the pawl 19 may straighten out in dead center manner when either of the notches 22 is opposite its free end. When the sector starts movement in either direction, the pawl passes from dead center position in the opposite direction so as to work in the reverse manner. The cooperation between the pawl and the sector plate is such as to require a complete movement of the shaft 4 and sector plate 17 in both directions, when once a movement of the shaft 4 is initiated. This full stroke pawl is a well known feature of calculating machines, and per se is no part of the present invention.

A suitable totalizer 23, Figs. 1, 2, 3, and 17, is mounted on the free end of a frame 24 (Fig. 17) which is pivoted at its other end upon a rod 25 so that the totalizer may rock or oscillate vertically to a limited extent about the longitudinal axis of the rod 25. This totalizer may be of any suitable construction with carry over or transfer mechanism, such as shown for example in the Peters and White patents and said copending application above mentioned, and shown also in Figs. 9a, 9b and 9c of this application. Such totalizers include a plurality of individual digit wheels 26, each of which carries on its periphery, in equally spaced relation thereon, the numerals zero to nine in numerical sequence. Each digit wheel has also attached thereto a pinion 27 by which that wheel may be driven in either direction.

Also extending between and rotatably mounted in the side members 2 and 3 of the frame is another or auxiliary shaft 28, Figs. 9 and 17, which, in this example, is disposed slightly to the rear of the main shaft 4. Fixed on the shaft 28 is an arm 29 which extends above and below that shaft. This arm 29 is disposed adjacent the side member 3 of the frame, and another arm 30, Fig. 9, is fixed on the shaft 28 near the side member 2 and extends upwardly therefrom. The

upper ends of the arms 29 and 30 are connected by a bar 31, Figs. 17, 24, 25, and 26, which has notches 31a (Fig. 26) in its rear edge to receive a plurality of rack arms 32 which are pivotally mounted on the auxiliary shaft 28 and are spaced apart and from arms 29 and 30 by suitable bushings 33 (Fig. 9). Mounted on the upper end of each rack arm 32 is a rack member 34 which slides in a direction from front to rear on the arm 32 to a limited extent, and is yieldingly urged toward the right (Fig. 9a) by a spring 35, to form a part of the carry over or transfer mechanism, as disclosed in said prior Peters patent. Each rack member 34 is disposed to mesh with the pinion 27 of a related digit wheel when the totalizer frame 24 is rocked downwardly into one position, and to be disengaged from the related pinion 27 when the totalizer frame 24 is rocked upwardly into its other possible position.

A plurality of digit stop bars 36 are disposed side by side but spaced apart, see Fig. 9, so as to extend in a direction from front to rear of the machine, the rear ends being individually pivoted by pins 37 to related rack arms 32. The forward ends of these stop bars 36 are received in notches or slots opening downwardly from the upper edge of a cross bar 38, Fig. 9, which extends between and connects the side members 2 and 3. An individual spring 39 is connected to each of the stop bars 36 and to the cross bar 38, so as to individually and yieldingly urge the stop bars 36 forwardly, unless otherwise restrained, until the connected rack arms 32 engage against the cross bar 31 which connects the arms 29 and 30 on the shaft 28. These stop bars 36 may, for convenience, be designated and distinguished beginning at the right and moving to the left in Fig. 9, as "units," "tens," "hundreds," etc., denominational stop bars. Each of the stop bars above the units denominational bar is provided with a depending lug 40, Figs. 12, 24 and 25, which by engagement with the cross bar 38 limits the extent to which the individual stop bars may be moved by their springs 39 in a forward direction. An individual stop arm 41 is provided for each of the stop bars 36, and is disposed side by side with its related stop bar and approximately at its mid-length is pivoted by a pin 42 to the related stop bar. These stop arms 41 generally extend parallel to the stop bars 36 to which they are connected and also extend through slots or notches in the upper edge of the cross bar 38, shown clearly in Fig. 9.

The lower edge of each stop arm 41, where it passes through a notch in the cross bar 38, is provided with a cam surface 43 which, by engagement with the bottom of the notch in which it slides, serves to cam that end of the stop arm 41 upwardly and lower the rear end thereof. An individual spring 44 is connected to the forward end of each stop arm 41, and to a cross bar 44a, Fig. 9, of the frame, at the bottom thereof, so as to yieldingly and individually urge the forward ends of the stop arms 41 downwardly and maintain them in the slots in the cross bar 38. The upper edge of each stop bar 36 is provided with a plurality of lugs 45 forming abutments 46, Figs. 24 and 25, which are spaced apart lengthwise of the bar so that by engagement with the lower ends of depressed keys on the keyboard, the forward movements of the bars may be limited as desired. Each stop arm 41 is also provided with upstanding lugs 47 spaced apart and providing abutments 48 which function similarly to the abutments 46 on the stop bars 36. These

stop bars with their stop arms thereon can move forwardly only when the rack arms 32 are released by the cross bar 31 carried by the upstanding arms 29 and 30.

5 In addition operations, the stop bars for a row in which no keys are depressed will be held against travel by zero stops at the forward end of the keyboard, as explained in said prior patents, and in such operations, the stop lugs 40 on the stop bars 36 have no function. When, however, a subtraction operation is performed, for all those rows of keys in which no key is depressed, the stop bars 36 for those rows of unoperated keys will be allowed to move for the 10 full extent corresponding to nine spaces, except for the units denominational stop bar 36, and that is allowed to move ten spaces if no key in the units denominational row is operated. For that reason, the stop lug on the units denominational stop bar 36 is omitted, but a similar lug 40a (Fig. 11) is placed on the stop arm 41 carried by that units denominational bar 36 and disposed rearwardly therein a distance of one unit of operation of the digit wheel, so that when the 15 handle starts its return operation in the second half of the cycle, the units denominational rack arm 32 will be picked up first and will move the associated digit wheel one space before any of the other rack arms will be picked up in the rows 20 25 in which no keys were depressed, so that the operation of the units denominational digit wheel through the ten spaces will cause a carry-over into the other wheels, which are moved only through nine spaces. This type of operation is 30 described on page 4, lines 72-102, of said White patent. The stop abutments 48 on the units denominational stop arm 41 are the tens complements of the corresponding stop abutments on the units denominational stop bar 36, but the 35 abutments 48 on the stop arms for all higher denominational orders are spaced thereon to represent the nines complements of the corresponding stop abutments 46 on the related stop bars 36. Each stop bar 36 and its attached stop 40 arm 41 may for convenience be considered and 45 referred to as a stop bar unit or stop unit.

Removably mounted on the frame is a standard keyboard 49, Figs. 12 and 17. This keyboard has notched ears 50 at its rear edge which straddle 50 and are supported by the cross rod 25, and depending lugs 50a at the sides of the forward portion which have slots in their lower edges which straddle and slide upon fixed studs 50b. In order to maintain the keyboard on the studs 50b, the forward end of the keyboard 49 is provided with a finger 52 which is secured to the keyboard frame 55 so as to depend downwardly from the forward edge thereof. This finger 52 has a rearwardly opening slot which straddles a forwardly-extending flange 51 of the cross bar 38 so as to confine the keyboard against vertical movement, yet by reason of the particular form of engagement between the finger 52 and flange 51, the keyboard is 60 free to slide a limited extent horizontally on the flange 51, the studs 50b, and rod 25. The finger 52 may be sprung forwardly sufficiently to disengage it from the flange 51 when one desires to remove the keyboard 49 from the machine. The ears 50 which straddle the rod 25 are disposed slightly nearer together than the distance 65 between the side members 2 and 3, as shown in Figs. 3 to 6, so that the keyboard may be shifted bodily in a horizontal or lateral direction from a position, such as that shown in Figs. 1 and 3, in 70 which the left hand lug 50 abuts against the side

member 2, to the right until the other ear or lug 59 abuts against the side member 3, as shown in Figs. 2 and 5.

A latch 54 (Figs. 4 and 6) is pivoted on the pin 55 on the flange 51 of cross bar 38, which latch, adjacent its free end, is provided with a notch 56. When the keyboard is moved bodily to the right from the position shown in Figs. 1, 3 and 4 to the position shown in Figs. 2, 5 and 6, the depending lug 50a on the keyboard will be brought into alignment with the notch 56, so that a spring 54a acting between the latch 54 and the cross bar 38 can urge the latch 54 in a direction to cause the notch 56 to straddle the lug 50a, as in Fig. 6. When the notch 56 is engaged over the lug 50a as shown in Fig. 6, it will prevent movement of the keyboard bodily to the left from the right hand position shown in Figs. 2, 5 and 6. The free end of the latch 54 has a lateral flange 58 by which this latch may be cammed into releasing position in a manner which will be explained herein later.

The base of the frame is provided with an up-standing lug 59, Figs. 13 and 14, upon which is pivoted, by pin 60, a bell crank lever 61, one arm of which is generally upstanding and is connected by a spring 62 to the side member 2. This up-standing arm of the bell crank 61 has a cam nose 63 which engages against the depending finger 52 on the keyboard so that by the tension of the spring 62, this bell crank 61 will yieldingly urge the keyboard back into the position shown in Figs. 1, 3 and 4. The keyboard, therefore, when free, will be automatically returned to its left-hand position shown in Figs. 3 and 4, yet it may be moved bodily to the right into the position shown in Figs. 2, 5 and 6, in which it will be latched by the latch 54.

The keyboard is provided with a plurality of rows of individually operable keys 64, Figs. 1, 2, 13 and 14, the keys in each row being designated from 1 to 9 in the direction from front to rear, as shown in Figs. 1 and 2, and the rows being disposed side by side. Each of these keys 64 is slidably mounted for vertical movement in the upper and lower plates 65 and 66 of the keyboard, and are yieldingly urged into their upper positions by springs 67, as disclosed more fully in the keyboards of said prior patents and application. Assuming that the keyboard is in its left-hand position shown in Fig. 13, the lower end of each key, when unoperated, is in close proximity to the lower face of the plate 66 of the keyboard, but when any key is moved downwardly, its lower end depends below the plate 66 into the path of one of the abutments 46 of the related stop bar 36, so as to limit, by its engagement with one of the shoulders 46, the extent of movement of the related stop bar 36. The keys of each row are releasably held in depressed or operated position by suitable latches or stops 68, one of which extends along each row of keys, so that after one key of that row is operated or depressed, the operation of another key of that row will cam the stop 68 aside momentarily and release the previously depressed key, all as disclosed in said prior patents.

At the front of the keyboard are a plurality of zero stops 69, each individually hinged to normally depend in front of the forward end of the stop bar 36 to which it is related, as shown in Fig. 13. When any key in a row related to any stop bar 36 is depressed, it cams aside this related zero stop 69 so as to release that related stop bar 36, as explained in said prior patents, and the

zero stop will remain in a position in which it releases its related stop bar 36, so long as any key in the related row of keys remains depressed.

When the keyboard is shifted to the right, as previously explained, this carries all of the zero stops 69 out of the path of the related stop bars 36 and also out of the path of the stop arms 41, even when a zero stop 69 is cammed aside by a depressed key, as shown in the tens row in Fig. 14.

10 Disposed across the forward edge of the keyboard is a key release comb or bail 70, which has lateral arms 71 pivotally connected by screws 72 to the side frame members of the keyboard. This bail 70 has comb-like teeth 73 (Fig. 14) which 15 extend rearwardly into positions to engage and cam aside all of the stops 68 and the zero stops 69, and thus release all the keys, as usual in keyboards of this type and disclosed in said prior patents. The laterally-extending arm 71 at the 20 right hand end of this key release bail or comb 70 has an extension 74, Fig. 7, which carries a laterally extending pin 75 and another laterally extending pin 76, so that by pressure exerted downwardly against the pin 75 or forwardly 25 against the pin 76, the key release bail 70 will be rocked clockwise, as viewed in Fig. 7, to release all of the keys of the keyboard. The pin 76 is disposed in a position to engage the cam lug 58 on the keyboard latch 54 and force it in a direction to 30 disengage the latch 54 from the keyboard, and thus release the keyboard for return to the left in Figs. 1 and 2. When the keyboard is in this left-hand position, as shown in Fig. 1, the engagement and operation of the latch 54 by the pin 76 35 will be immaterial, because the latch 54 by its abutting engagement of an unnotched portion thereof against the edge of the depending lug 50a of the keyboard frame, will keep the lug 58 generally out of the path of the pin 76, but when 40 the latch 54 is in latching engagement with the keyboard frame, the lug 58 will be shifted into the path of movement of the pin 76, when the key release bail 70 is operated to release the keys. Thus, whenever the keys are released, the keyboard 45 will also be unlatched and free to return to the left into the position shown in Fig. 1.

Also fixed on the main shaft 4 (Fig. 17) is an arm 77 which at its free end is pivotally connected by a pin 78 to one end of a link 79, the 50 other end of that link being pivotally connected by a pin 80 to a depending end of the arm 29. The arm 77 extends forwardly at a small inclination upwardly when the shaft 4 is in its normally inactive position, as shown in Fig. 17, and when 55 the shaft 4 is operated through a cycle of movement, such as counter-clockwise in Fig. 17, this movement will cause the lower end of the arm 29 to swing rearwardly and the cross bar 31 to move forwardly and release the rack arms 32. These 60 rack arms then move forwardly to the extent permitted by the stop units connected thereto and the latter are controlled by any depressed keys of the keyboard or by the zero stops. As the shaft 4 returns to its initial position, the cross bar 31 65 will pick up all of the rack arms and carry them rearwardly to the initial positions shown in Fig. 17.

The totalizer frame 24 (Fig. 10) adjacent its right hand end is provided with a depending integral arm 81, which carries at its lower end a laterally extending pin 82 mounting a roller which runs in a cam groove or slot 83 which is provided in a lever 84. The lever 84 is pivoted on a stud 85 carried by the inner face of the side member 3. The slot or cam groove 83 is formed with one end

of the slot or groove 83 nearer the axis of the stud 85 than the opposite end. This lever 84 has another arm 86 which carries a pin 87 that is engaged and cammed in one direction by an arm 88, fixed on the main shaft 4 in a position such that when the main shaft approaches its limit of movement at the end of a complete cycle, the arm 88 will engage the pin 87 and rock the lever 84 in a direction to cam the roller on the pin 82 into the end of the slot 83 which is farthest from the stud 85. This movement of the roller 82 into the end of the slot 83 farthest from the stud causes the arm 81 to rock the totalizer frame 24 counter-clockwise about the rod 25, as shown in Fig. 10, to carry the pinions 27 on the digit wheels into mesh with the rack members 34.

A spring 89 is connected at one end to a pin 90 carried on another arm 91 of the lever 84, the other end of the spring 89 being secured in any suitable manner to the side frame member, as by a pin 91a, Fig. 7. The spring 89 serves to yieldingly urge the lever 84 in a direction to raise the totalizer until the pinions on the digit wheels are disengaged from the rack members 34. The pin 90 extends through an aperture 92 in the side member 3 into a position beneath a latch 93, Fig. 7, which latch 93 is pivoted on the stud 94 extending from the outside face of the side member 3. This latch 93 is urged downwardly yieldingly by a spring 95 which is coiled about the pivot stud 94, with one end hooked over the upper edge of the latch 93, and the other edge hooked over the edge of aperture 92 in the side member 3. The latch 93 is provided with an abutment shoulder 96, and some distance from the shoulder 96 in a direction further from the pivot stud 94, this latch has a depending arm 97. The full stroke sector 17 carries a roller 98 which is disposed to engage with the lower end of the depending arm 97 of the latch 93 when the main shaft 4 approaches its limit of movement at the end of a complete cycle of operation, which action raises the latch 93 until the shoulder abutment 96 is above the path of the pin 90 and allows the lever 84 to be rocked under the action of the spring 89. When the lever 84 is thus freed for movement by the spring 89, it will rock counter-clockwise (Fig. 10) until the pin 87 on the lever engages the arm 88 on the main shaft 4, which arm has returned almost to its home position at this time and limits the movement of the lever 84 to such a small extent that the relative movement between the cam groove 83 and the pin 82 will not be sufficient to cause the totalizer to be disengaged from the rack members 34. Continued movement of the arm 88 to home position will cause the lever 84 to be moved to its home position, as shown in Fig. 10, and will cause the totalizer to be retained in engagement with the rack members at the end of the operation.

The full stroke sector is also provided with an arm 99, Fig. 7, which, as the shaft 4 is about to complete its first half cycle of operation, will engage with the pin 90 that projects through the aperture 92 and rock the lever 84 in a direction opposed to the spring 89, so as to cause a lowering of the totalizer until the pinions on its digit wheels engage with the rack members 34. The abutment shoulder 96 on the latch 93 is disposed to engage behind the pin 90 and hold the lever 84 in the position shown in Fig. 10, in which the totalizer has driving engagement with the rack members 45. This latch engagement is also shown in Fig. 19.

A total key 100, Figs. 7 and 10, is pivoted on

a rod 101 which extends between the side members 2 and 3 of the frame and also serves to support some of the carry-over mechanism for the totalizer. This key 100 (Fig. 10) is in the form of a bell crank, and an arm 102 thereof is pivotally connected by a pin 103 to a link 104. This link extends downwardly and at its lower end is pivotally connected by a pin 105 to a plate 106 that is pivoted on a stud 107 carried on the inner face of the side member 3. This plate 106 is provided with an arm 108 which is pivotally connected by a pin 109 to one end of a link 110, the other end of which is pivotally connected by a pin 111 to a lever 112 that is pivoted on a stud 113 carried by said side member 3. The lever 112 extends upwardly adjacent the front of the machine and has a cam edge 114 disposed in a position to engage the pin 76 on the key release bail or comb 70 and rock the latter to cause a release of all depressed keys of the keyboard. The plate 106 is also provided with an edge cam surface 115 which is approximately concentric to the axis of the stud 107. This concentric cam surface 115 merges at its lower end into the base of a V-shaped tooth 116 and the other base of this tooth merges into another cam edge 117 which is nearer the axis of the stud 107 than is the surface 115.

A lever 118, Figs. 7 and 10, is pivoted on a stud 119 on the side frame member of the keyboard, and this lever has a rigid arm 120 (Fig. 7) which extends rearwardly and terminates in an upstanding arm 121 which, at its upper end, is normally below the path of travel of the pin 90 on the lever 84. The lower end of this lever 118 has a lateral flange 122 which is adapted to abut edgewise against the cam surfaces 115 and 117, and the surfaces of the V-shaped tooth 116 of the plate 106. When the flange 122 is riding against the cam surface 115, the lever 118 will be in the position shown in full lines in Figs. 7 and 10, and the upstanding arm 121 will be just below the path of travel of the pin 90, so as not to interfere with the rocking of the lever 84.

When the flange 122 is riding against the cam surface 117, which is nearer the axis of the stud 107, then the lever 118 will occupy a position shown in Fig. 20, in which the upstanding arm 121 has moved up into a position behind the pin 90 so as to prevent any material movement of the pin 90, and thereby prevent any oscillatory movement of the lever 84. The lever 118 is also provided with a forwardly extending arm 123 (Fig. 7) to which is connected one end of a spring 124, the other end of which is anchored to the lower plate 66 of the keyboard frame. This spring 124 urges the lever 118 in a direction to carry the upstanding arm 121 upwardly behind the pin 90, and the edge of the arm 121, against which the pin 90 abuts, is approximately normal to the radius from the pin 90 to the stud 119, so that the pressure exerted by pin 90 on arm 121 will not produce any rotation of the lever 118.

A one-way pawl 125 (Fig. 7) is pivoted on the stud 126 on the lower end of lever 118, and a spring 127 is connected at one end to a pin 128 carried on the pawl 125 and at its other end to the lever 118. The pin 128 engages against an edge of the lever 118 so as to limit the extent of movement of the pawl 125 by the spring 127, as shown in full lines in Fig. 7. The pawl 125 which projects beyond the end of lever 118 may, however, rock clockwise (Fig. 7), which tensions the spring 127 and moves the pin 128 away from the edge of the depending arm of the lever 118. A roller 129, Figs. 7 and 10, is carried by a stud

130 provided on the inner face of the full stroke sector 17, and at a radial distance from the axis of the shaft 4 such that when the shaft 4 is rocked in a cycle of operation, the roller 129 will pass and clear the pawl 125 when the lever 118 is held in the full line position shown in Fig. 7 with the flange 122 resting against the cam surface 115. When the plate 106 is rocked from the position shown in full lines in Figs. 7 and 10 to the position shown in full lines in Fig. 20, the lever 118 will be moved counter-clockwise by its spring 124 to raise the arm 121 into a position to block movement of the pin 90 and through it block movement of the lever 84. In this movement of lever 118, the pawl 125 moves nearer the axis of the main shaft 4 until flange 122 engages surface 117 of plate 106, and then when the main shaft 4 operates through the cycle of operation, the roller 129 on the full stroke sector 17 will engage the pawl 125 during the first half of the cycle of operation of the shaft 4 and pass idly by, the pawl pivoting against the action of spring 127 at this time. When, however, the full stroke sector returns during the second half of the stroke, the roller 129 will engage against the blunt end 131 of the pawl 125 and force the pawl sidewise, which rocks the lever 118 clockwise to tension its spring 124 and withdraw the upstanding arm 121 from its position behind the pin 90. This releases the pin 90 for movement by its spring 89, and as the roller 129 continues its movement with the full stroke sector, it cams the lever 118 further in the same direction to carry the flange 122 clear of the V-shaped tooth 116. Then when the pawl 125 is released by roller 129, the flange 122 may again engage with the cam surface 115.

A spring 132, Figs. 10, 20, 22 and 23 is connected at one end to the link 104, and at its other end to a pin on the side member 3, so as to yieldingly urge the link 104 endwise and downwardly, which is in a direction to rock the plate 106 into the position shown in full lines in Fig. 10, where the flange 122 can engage the cam edge 115. The link 104 is provided at its upper end with a rearwardly extending arm 133, Fig. 10, which extends beneath a laterally bent lug or extension 134 on the latch 93. The lug 134 projects through the aperture 92 in the side member 3 because the latch 93 is on one face of the side member 3 and the arm 133 is disposed at the opposite face of said side member 3. When the link 104 is moved endwise and upwardly by rocking of the total key 100 in a counter-clockwise direction in Fig. 10, this will carry the arm 133 upwardly and lift or hold the lug 134 on the latch 93 in the position shown in full lines in Fig. 22. The latch 93 is thus held above the pin 90 so that the abutment shoulder 96 will clear the pin 90 when the latter is rocked by its spring 89 to the right as in Fig. 22. The engagement of the arm 102 of the total key 100 with a stud 135, Figs. 10, 20 and 22, limits the extent of movement of the key 100 in one direction.

A repeat key 136 (Fig. 7) is mounted by a stud 137 on the right hand side frame member of the keyboard, as usual in this type of machine and as disclosed in said patents and copending application. This key 136, at its lower end, is provided with notches 138 and 139 spaced apart along the lower end edge of the key. A pin 140 carried by a lever 141 rides against the lower end edge of key 136 so as to enter the notches 138 and 139 alternately when the key 136 is rocked back and forth. The lever 141 is mounted on a stud

142 which is carried by the side frame member of the keyboard. A spring 143 acting between the lever 141 and stud 137 yieldingly urges the lever 141 in a direction to cause its pin 140 to bear against the lower end of the key lever 136 and enter either of the notches 138 and 139 that are alined therewith. The repeat key lever 136, stud 137, and lever 141 are carried by the keyboard and move from side to side of the machine therewith.

Also rockably mounted on the same side frame member of the keyboard is a key release lever 144, Fig. 7, which has at one end a depending arm terminating in a cam edge 145 in a position to be engaged and operated by the roller 129 on the full stroke sector 17. An oppositely extending arm on the lever 144 carries a one-way bypass pawl 146 which moves with the lever 144 in a path to engage the pin 75 on the extension 74 of the lateral arm of the key release bail arm 71. The pawl 146 is held against a stud or pin 147 by a spring 148, so that when the pawl 146 is moved upwardly with the lever 144 to engage the pawl 75, the pawl 146 will snap idly by the pin 75, but when the lever 144 then rocks in the opposite direction, the pawl 146 will not be cammed aside by pin 75 but will serve as a rigid extension of the lever 144 and cam aside the pin 75 and thereby cause a rocking of the bail 70 in a manner to cause a release of any operated keys in the keyboard. The lever 144 is yieldingly urged in a clockwise direction (Fig. 7) by a spring 144a acting between the pivot pin for the pawl 146 and the stud 137.

Independently and rockably mounted on the stud 137 is a lever 149, Fig. 7, which carries at its forward end a laterally extending pin 150. The forward end of lever 149 overlies the extension 74 on the key release bail 70 so that when the lever 149 is rocked counter-clockwise in Fig. 7, its forward end will engage the extension 74 and rock the bail 70 in a direction to release any operated keys. The pin 150 is disposed below and alined with a correction key 151, Figs. 1 and 2, so that operation of the correction key will rock lever 149 counter-clockwise in Fig. 7, and by rocking the bail 70, will release any keys that have been operated and not released. A spring 152 urges the lever 149 in a clockwise direction in Fig. 7. The end of the lever 149, opposite from the pin 150, is provided with an upstanding hook 153 which normally clears the upstanding member 154 on the lever 144, but which may move upwardly and block movement of the arm 154 of lever 144 when the lever 149 is rocked counter-clockwise in Fig. 7. A pin 155 on the lever 149 engages beneath the arm 123 on lever 118, so that when the lever 149 is rocked counter-clockwise in Fig. 7, the pin 155 will engage arm 123 and rock the lever 118 in a direction to withdraw the upstanding arm 121 from the path of the pin 90 and move the flange 122 clear of the tooth 116 so as to release the plate 106 if the plate should have been latched by the flange 122 in its operative position.

The mechanism is enclosed within a suitable housing 156, Figs. 1, 2, 7 and 17, which has an opening 156a through which the repeat key 136 may project with sufficient clearance to enable 70 rocking forwardly of the repeat key, and also sidewise movement of the repeat key with the keyboard between the positions shown in Figs. 1 and 2. The housing also has a slot 157 through which the total lever 100 may project with sufficient clearance for its operation, and a window

158 through which the digit wheels of the totalizer may be viewed.

The comb extension 13 of the key release bail 10, Fig. 14, are urged upwardly by the latch bars 68 and the zero stops 69 which are resiliently urged in the usual manner toward the rows of keys to which they are related, and the extension 14, Fig. 7, has, adjacent the pin 76, a laterally extending portion 159 which engages beneath a projecting flange of the bottom plate 66 of the keyboard so as to limit the upward movement of the extension 14 of the key release bail.

In order to prevent too rapid an operation of the main shaft 4, that shaft, Figs. 9 and 17, is provided with another arm 160 fixed thereon, which is pivotally connected by a pin 161 to a piston rod 162, extending into a dash pot cylinder 163. The rod 162 within the cylinder 163 has a piston running in the cylinder so as to control the rate of movement of the shaft 4, as old in this art.

The transfer mechanism between digit wheels of the totalizer is substantially the same as disclosed in said prior patents and said copending application and as used for many years commercially in Allen Wales calculating machines. It is shown briefly for the purpose of the record in Figs. 9a, 9b and 9c and will be briefly referred to. Secured to each digit wheel is a cam 165 which rotates with its digit wheel counterclockwise in Figs. 9a, 9b and 9c in addition and subtraction operations, but which rotates in the opposite direction when the digit wheels are all set to zero during a total clearing operation. When the machine is idle and the totalizer is cleared, the parts are in the position shown in Fig. 9a, in which the digit wheels are all at zero and a nose 166 of the cam for each wheel below the highest digit wheel is in the position shown in full lines, immediately behind a laterally extending lug 167 on a transfer lever 168 which is pivoted on a rod 169 and is used to extend the carry over control to the next higher digit wheel. A lever or latch 170 for each lever 168 is pivoted on the rod 171 supported by the machine frame and has a laterally extending flange or lug 172 which engages alternately against step-like abutments 173 and 174 arranged in spaced relation to each other along the lever 168. There is a lever 168 and a latch 170 for each transfer between digit wheels, and each lever 168 is yieldingly and individually urged upwardly by a spring 175 to the extent permitted by the engagement of its upper edge with the lug 172 of latch 170. The spring 175 acts between each lever 168 and an arm 176 of the related latch 170, so as to urge the latch 170 counterclockwise in Figs. 9a, 9b and 9c.

When the frame 24 is raised upwardly at the beginning of an operation of the shaft 4, when adding or subtracting, it will engage all of the arms 176 and rock all of the latches 170 clockwise to carry the lugs 172 in front of the abutments 174, and when that happens, the springs 175 snap the levers 168 upwardly. This relation of parts is shown in Fig. 9c, which also shows the lug 172 of the latch 170 slightly spaced away from the related abutment 174. When any digit wheel passes below the highest denomination wheel during its rotation counterclockwise in Fig. 9a, the cam nose 166 of its cam 165 will have engaged the lug 167 and cammed the lever 168, which cooperates with the rack member 34 associated with the next higher de-

nomination digit wheel, whereupon the related latch 170 snaps its lug 172 against abutment 173 on the higher step so as to hold lever 168 depressed, as shown in Fig. 9b. Each lever 168 has a pair of spaced lugs 177 and 178 which are disposed with ends at different levels across the width of the lever and also spaced apart along the lever 168. Each rack member 34, as explained in said prior patents, is capable of limited movement endwise on its rack arm 32, an amount sufficient to cause a movement of the digit wheel one digit or space. When the rack arms 32 move forwardly during an addition or subtraction operation, the rack members 34 are out of engagement with the digit wheel pinions, and each spring 35 before mentioned, which acts between its rack member 34 and rack arm 32, urges that rack member 34 to the right in Fig. 9a.

When the main shaft 4 moves during its back stroke, the digit wheel pinions are in mesh with the related rack members 34, and as the rack arms 32 are picked up by the cross bar 31, the digit wheels will be rotated amounts determined by the positions of the rack arms 32 when picked up by the cross bar 31, until a laterally extending lug 180 on each rack member 34 engages with the lowermost and first encountered lug 177 on the related lever 168. This stops the further movement of the rack member 34, although the related rack arm 32 moves a distance of one digit space further during which the spring 35 is tensioned. If any lever 168 is, however, latched in the position shown in Fig. 9b because the next lower digit wheel had just passed into or through zero position, the lug 180 on that lever, instead of striking the abutment 177, will pass above it until it strikes abutment 178, thus giving further movement of one digit space to the digit wheel above the wheel on which cam 165 is fixed and which cam has just latched the lever 168 in the Fig. 9b position. At the next forward movement of the main shaft, the totalizer frame 24 is at once rocked upwardly and its engagement with the arms 176 of all the transfer latches 170 will rock the latter into the positions shown in Fig. 9c so as to reset all transfer mechanism for a new transfer operation.

When the totalizer or accumulator is to be cleared, the operator rocks the total lever 168 rearwardly and this moves the upstanding arm 121 of arm 120 behind the pin 90 to prevent rocking of the totalizer upwardly when arm 83 releases lever 84 as the shaft 4 starts a cycle of operation. The rack arms 32 as they are released by cross bar 31 will be urged forwardly, and will rotate the digit wheels, with which they are in driving relation, until the lugs 166 on the cams 165 carried by the digit wheels engage the related lugs 167 (during this clockwise rotation of cams 165) in Figs. 9a, 9b and 9c. Further movement of the rack arms 32 is then prevented, although the cross bar 31 continues its forward movement. When the main shaft starts the second half of its cycle, the totalizer is at once elevated until the digit wheel pinions are disengaged from the rack members 34, and the rack arms 32 are returned to initial position by the cross bar 31. This elevation of the totalizer is caused by the action of roller 129 on pawl 125 which cams lever 118 clockwise in Fig. 7 and releases pin 90. Since latch 93 is at this time held elevated by arm 133, the pin 90 when released in this manner is moved rearwardly by its spring 89. This causes an elevation of the totalizer. Thus the transfer mechanism is used to stop all of the

digit wheels in zero positions, which leaves the totalizer in a cleared condition.

When the same number or item is to be run into the totalizer a plurality of times in succession in performing a calculation, either addition or subtraction, the operator may shift the repeat lever 136 rearwardly from its inactive position shown in Fig. 7 until the pin 140 rides in the notch 138, which serves to yieldingly hold the repeat key 136 in its rearward or repeat position. A pin 181 is provided on the lever 144 in a position to move into the notch 138 when the repeat key is in its normal inactive position shown in full lines in Fig. 7, which allows the lever 144 to rock far enough to carry the pawl 146 upwardly past the pin 75 on the key release bail. However, when the repeat key 136 is moved rearwardly to carry the notch 138 into alignment with the pin 149 of the latch, the pin 181 will engage, when the lever 144 is released and rocked by its spring 144a, against an unnotched periphery at the lower end of the key repeat lever 136, which prevents the movement of the lever 144 under the action of its spring 144a sufficiently to carry the pawl 146 past the pin 75. Then when the roller 129 again rocks the lever 144 at the end of a cycle of operation of the main shaft 4, there will be no rocking of the key release bail 70, and hence no release of the keys that have been set. Then, every time that the main shaft 4 is operated through a cycle of operation, the same number which remains set up in the keyboard will be the item that is run into the totalizer. Since the key release bail 70 is not operated automatically during a cycle of operation of the main shaft 4 while the repeat key is moved rearwardly into repeat position, the latch 54 will not be operated by the pin 76 of the key release bail 70, and hence the keyboard if in subtraction position will remain in that subtraction position, and not be released until the repeat key 36 is returned to its normal, non-repeat position shown in full lines in Fig. 7.

A detent lever 182, Fig. 10, is pivoted by pin 183 to the lever 84, and it normally rides upon a pin 184 fixed on the side member 3 of the frame of the machine. The edge of the lever 182 which engages pin 184 is provided with two notches 185, which are spaced apart along that lever and alternately engage over the pin 184 when the lever 84 is rocked back and forth to shift the totalizer into and out of operating relation to the rack members 34. A spring 186 is anchored at one end to the arm 86 of lever 84, and at its other end to an upstanding tail on the lever 182, so as to yieldingly rock the lever 182 in a direction to engage against pin 184. Thus, as the lever 84 is rocked to position the totalizer in either of its two positions, the engagement of one of the notches 185 with the pin 184 will aid in locating the totalizer definitely in the position into which it has been shifted and in yieldingly holding the totalizer in that position.

In the operation of a calculating machine of the type illustrated, the keyboard of the machine will normally be in the position shown in Fig. 1, which will be the left-hand position. If one desires to add numbers to the items already in the totalizer, as shown through the window 158, one depresses a key in each of the rows which represents the number to be added, a key being depressed in the proper digit row for each digit of the number to be added. Then the operator pulls the handle forwardly as far as it will go and releases it for return to its rearward position

under the action of the spring 7. If the machine is motor-operated, the operator, instead of operating the handle, merely pushes a key (not shown) which causes operation of a motor for a cycle that operates the main shaft 4, as well known in the art. The depressed keys present their lower ends over the stop bars 36 immediately thereunder. In Fig. 13, the number 3 key in the tens denominational row is shown as depressed, and its lower end has moved down into the path of one of the abutments 46 of the related tens stop bar 36, as shown in Figs. 12 and 15. When the key in the tens denominational row was depressed, it cammed aside the zero stop 69 for that row of keys, as shown in Fig. 13.

When the main shaft starts its cycle of operation for addition, the arm 88, Fig. 10, at once releases the pin 87 of lever 84, and the spring 89 then rocks lever 84 in a direction to cause an elevation of the totalizer frame so as to disengage the pinions of the digit wheels from the rack members 34. At the same time the shaft 4, through the link 79, Fig. 17, rocks the lever 29 counterclockwise and moves the cross bar 31 forwardly so as to release all of the rack arms 32. The springs 39 acting on the stop bars 36 urge them all forwardly, but only the stop bars 36 which have been released from the zero stops can move forwardly because the other stop bars 30 will be held against forward movement by the zero stops. Since, in this example, only the number 3 key in the tens denominational row was operated, only its lower end is in a position to engage the number 3 abutment 46, which is the first abutment to the rear of the depressed key. This determines the extent of movement of that stop bar 36. The distance from the lower end of each key to the first abutment to the rear thereof will determine the extent of movement 40 of the bar 36 for that row when that key is operated. The cross bar 31 will continue its forward movement after the stop bars are stopped by the keys or the zero stops.

When the main shaft 4 is completing its first half of its cycle of movement, corresponding to the forward movement of the handle 5, the arm 99 on the full stroke sector 17 will engage the pin 90 and cam it forwardly until it passes the abutment 96, whereupon the spring 95 rocks the latch 93 downwardly so as to engage the abutment 96 behind the pin 90 (Fig. 19) and hold the totalizer in its downward position, with its digit wheel pinions in mesh with the rack members 34. The totalizer having now been shifted into driving engagement with the rack members, as soon as the main shaft 4 starts its last half of its cycle of movement, the cross bar 31 will move rearwardly, and during its travel will engage and move with it any of the rack arms 32 which have moved forwardly and which, in this selected example, is only the rack arm for the tens denominational order. In carrying that rack arm back to its rearward position, the rack member 34 for that digit wheel will rotate it an amount 65 represented by the extent of forward movement of the tens denominational rack arm 32. This introduces into the tens denominational digit wheel of the totalizer a number corresponding to the depressed key. If the digit wheel, in moving 70 in this manner, passed the zero position, it caused a transfer to the next higher digit wheel by the transfer mechanism illustrated in Figs. 9a to 9c, and as illustrated and explained in said Peters patent.

As soon as the shaft 4 began its cycle of move-

ment, as just explained, the roller 129 released the lever 144 and the latter was then rocked by its spring 144a clockwise in Fig. 7, so as to carry the pawl 146 upwardly past pin 75 on the key release bail 70, the pawl pivoting freely against its spring 148 so as to pass pin 75 without rocking the bail 70. When the shaft 4 is about to complete a full cycle, represented by a return of the handle to its rearward position, the roller 129 again engages the cam edge 145 and rocks the lever 144 counterclockwise in Fig. 7, so as to carry the pawl 146 downwardly past the pin 75. The pawl 146 cannot yield in this direction, and hence it cams the pin 75 downwardly, which causes a rocking of the bail 70 clockwise in Fig. 7, and the comb-like projections 13, Fig. 14, engage the latch bars 68 and zero stops 69 and cam them aside so as to release all depressed keys in all the rows, thereby enabling those keys to return to their elevated positions.

At about the same time that the roller 129 rocks the lever 144 in this manner, the roller 98 also engages the depending arm 97 and cams it upwardly to release the pin 90 from behind the abutment 96, thus releasing the lever 84 to the action of the spring 88, which rocks the lever 84 a slight distance which is insufficient to cause the totalizer to be disengaged from the rack members. The engagement of the portion of the edge of the full stroke sector adjacent the roller 129 with the buffer element 10 causes a buffer action through the action of the spring 14, Fig. 7, which cushions the forward movement of the main shaft 4. Any desired number of items may be entered in the totalizer by setting the numbers or items up in the keyboard and causing operation of the main shaft 4, after each item is set up, in the manner just explained.

If one desires to perform subtraction, one grasps the key 136 and moves it to the right from the position shown in Fig. 1 to that shown in Fig. 2, which action shifts the keyboard bodily to the right from the positions shown in Figs. 1, 3 and 4, representing the adding position, to the subtraction position, shown in Figs. 2, 5 and 6. When the keyboard moves to the right in this manner, the lower ends of the keys, which cooperate with the stop bars, are all shifted to the right, so that instead of cooperating with the abutments of stop bars 36, as shown in Fig. 13, the lower ends of the keys will be above the stop arms 41 carried by the related stop bars 36, as shown in Fig. 14. When the keyboard moves bodily to the right, it tensions the springs 62, because the depending finger 52 acts against the cam nose 63 on lever 61 and rocks it from the position shown in Fig. 13 to the position shown in Fig. 14.

When the keyboard moves to the right in this manner, it also carries all of the zero stops 69 from blocking position at the ends of the stop bars 36 into positions to clear all stop bars 36 and attached stop arms 41, as shown in Fig. 14. Then, to set up an item for subtraction, one merely depresses the keys 54 in the different rows to represent that item, and in the particular example illustrated, suppose that a key in the tens denominational row was depressed, as shown in Fig. 14, that would shift the zero stop for that row further clear of the stop arm 41, and the lower end of that depressed key, instead of depending into the path of the abutments on the stop bar 36, shown in Fig. 15, would depend into a position immediately above the stop arm 41 on the tens denominational stop bar shown

in Fig. 16. Then a cycle of operation of the shaft 4 is initiated by the operation of the operating motor or by manually operating the handle 5 forwardly to the full extent required by the full stroke sector and pawl 19, and then releasing the handle 5 for return by its spring 7 to its rearward position.

When the shaft 4 began this cycle of operation, the lever 144 was released and operated clockwise, as explained for addition, and the roller 98 released the latch 93. The rest of the operation is the same as above, except that all of the stop bars 36, except for the tens and units denominational order, will move forwardly to the full extent corresponding to that required to move their digit wheels through nine spaces. When stop bar 36 for the tens denominational order moves forwardly, the movement continues until one of the abutments 48 on that tens denominational stop arm 41 engages the lower end of the depressed key. Assuming that the number 3 key in the tens denominational row was depressed, as shown in Figs. 27 and 28, the forward movement of the stop bar unit for the tens denominational order would continue until the cam 43 on the lower edge of that stop arm 41 engaged the cross bar 38, and then the arm 41 would be rocked clockwise in Figs. 27 and 28 through continued forward movement of that stop bar unit. This enables the number 2 stop abutment on the tens denominational stop arm 41 to pass the number 3 key which is depressed, and then the stop arm 41 is rocked to bring the number 3 stop abutment thereon upwardly into position to engage the depressed number 3 key. This determines the forward movement of that stop bar unit, which is an amount corresponding to the nines complement of the number represented by the key which is depressed, which in this instance for the number 3 key would be six spaces.

In the case of each of the keys 2, 3, and 4 in each of the denominational orders except the units order, and in the case of the 2, 3, 4, and 5 keys in the units order, the rocking action of the arms 41 is necessary in order to prevent these keys from coacting with the preceding stops on the arms 41. For example, in the case of the tens, hundreds, and higher orders of the machine, the 2 key stem lies in front of the 1 stop on the arm 41 when the key is depressed. Similarly, the 3 and 4 key stems lie in front of the 2 and 3 stops on the arm 41. Hence, if provision were not made for allowing the stop arm to move underneath these stops, improper operation of the machine would result. The same is true in the units order except that in this case the 2, 3, 4, and 5 key stems lie in front of the 1, 2, 3, and 4 stops on the stop arm. This relationship results from the fact that the throw of the stop arms in moving from 1 to 9 or 1 to 10, as the case may be, is greater than the space between adjacent key stems, and hence some overlapping between the key stems and the stops on the arms is necessary. The difficulty is taken care of, however, by pivoting the arms 41 at 42 and allowing the arms to move forward in their depressed positions through approximately one-half of their forward travel, after which they are cammed up into engaging position by the cams 43. The coaction between the 6, 7, 8, and 9 keys and their related stops on the arms 41 is not affected by this pivoting action, since, when these keys are depressed, the arms are stopped before the cams 43 reach the plate 38,

and hence no pivoting action of the arms occurs. All of the other stop bar units move forwardly until their lugs 40 or 40a engage the cross bar 38, which is an amount such that when returned to initial position, they will move all their related digit denominational wheel above the units wheels through nine spaces and the units denominational digit wheel through ten spaces because the units denominational stop bar unit moves one space further than the others due to the fact that the lug 40a on the stop arm 41 for the units denominational bar is set back a distance of one space beyond the lugs 40 of the other stop bar units. At the end of the first half of the cycle of operation of the main shaft, the totalizer will be shifted back into driving engagement with its rack members, and as the main shaft returns to its initial position, the cross bar 31 will pick up the different rack arms and move them rearwardly, and thus rotate the individual digit wheels in the same direction, as in addition, so as to add or run into the digit wheels the complements of the numbers represented by the depressed keys. At the end of the return movement, the roller 129 rocks the lever 144 and causes a rocking of the key release bail 70. Whenever the key release bail 70 is rocked in this manner in subtraction, the pin 76 will engage the lug 58 and rock the latch 54 so as to disengage that latch from the depending lug 50a of the keyboard, whereupon the keyboard is automatically returned by its spring 62 to its left-hand or normal adding position, if it had been displaced for subtraction purposes. Thus, at the end of each subtraction operation, the keyboard is returned to its normal adding position, and for each new subtraction operation, the keyboard should be shifted to the right before the subtraction operation of the main shaft is initiated.

As explained previously, the units denominational stop bar unit moves forwardly a distance represented by one space beyond the other stop bar units and, therefore, when the main shaft begins its return movement, the cross bar 31 will pick up the units denominational rack arm 32 and move the units denominational digit wheel a distance of one space before any of the other digit wheels are operated, so that if a carry-over is required, it will be performed during the last space movement of the digit wheels at the end of the cycle of operation of the main shaft. If, as in this selected example, no key was depressed in the units denominational row, but the keyboard is set for subtraction, operation of the main shaft will cause the units denominational digit wheel to be rotated through a complete rotation, which would cause a transfer of one digit into the tens denominational wheel into which only a nines complement is added by its stop bar unit.

When one desires to clear the totalizer, after calculations have been completed, the total key 100 is rocked rearwardly from the positions shown in Fig. 7 to the positions shown in Figs. 20 and 22. Movement of this key 100 in this manner moves the link 104 upwardly, Figs. 20 and 22, and the arm 133 thereon engages the lug 134 of the latch 93 and raises it so as to clear the abutment 96 from the path of movement of the pin 90. The link 104 also rocks the plate 106 clockwise in Fig. 22, during which movement the nose or tooth 116 cams the flange 122 aside, which rocks the lever 118 idly and then releases it, whereupon the lever 118 is rocked to carry the flange 122 into engagement with the cam surface 117 which is nearer the shaft 107 than

was the surface 115. This enables a rocking of lever 118 counterclockwise in Fig. 22 sufficient to move the upstanding arm 121 into a position behind the pin 90 and thus prevent movement of pin 90 in a manner to rock the totalizer upwardly and disengage it from the rack members 34 as soon as the totalizer is released by movement of the arm 88 away from the pin 87, Fig. 10. At the same time the engagement of the flange 122 beneath the tooth 116 on plate 106 serves to latch the plate 106 in that position against the action of the spring 132, so as to hold the clearance key 100 in its operative position.

When the lever 118 moves in this manner, it moves its pawl 125 into the path of travel of the roller 129. The plate 106, when it was rocked into the position shown in Fig. 20, also acted through the link 110 to rock the lever 112 counterclockwise in Fig. 20, so as to cause the end 114 thereof to engage the pin 76 on the key release bail 70 and rock the latter in a manner to release any operated keys. The same movement also served to operate the latch 54 to release the keyboard for return to its left-hand position if the keyboard had first been shoved into its subtract position, as shown in Fig. 2, without performing a subtraction operation and before the total key 100 is operated to cause a total clearing operation to clear said totalizer. As soon as the main shaft 4 begins its cycle of movement, the roller 129 releases lever 144 and roller 98 releases the latch 93, but the latter remains in its elevated or unlatched position through the action of the arm 133 which has engaged beneath the lateral lug 134 on latch 93.

The pin 90 is held against rearward movement under the action of its spring 89, notwithstanding the elevated position of the latch 93, because such movement is prevented by the upstanding arm 121 which was moved into the position shown in Fig. 20, upon operation of the total key 100. The totalizer is thus held in its lowered position in driving engagement with the rack members 34, and as the cross bar 31 moves forwardly, all of the rack arms 32 are free to move forwardly and cause a rotation of the digit wheels in the opposite direction, which is clockwise in Fig. 17, until the cam lugs or noses 166 on the digit wheels engage the lugs 167 of the transfer levers 168, see Fig. 9a, and then further movement of the digit wheels is prevented. Since the digit wheels cannot rotate further in this reverse direction, the rack arms 32 will remain in the positions in which they are stopped while the cross arm 31 continues its forward movement. As the shaft is about to complete the first half of its cycle of movement, the roller 129 passes the pawl 125 on the lower end of lever 118, the pawl 125 swinging idly to allow roller 129 to pass.

As soon as the shaft 4 starts its return or second half of its cycle of movement, the roller 129 will engage the pawl 125, but since the pawl 125 cannot now swing on its pivot to allow roller 129 to pass, this action will cause the lever 118 to be cammed aside, clockwise in Fig. 7, which removes the arm 121 from the path of the pin 90. Since the latch 93 is still held elevated, the pin 90 can now be moved by the spring 89 to elevate the totalizer and disengage it from the rack members. This removes the digit wheels from driving engagement with the rack members and then, as the shaft continues its return movement to its initial position, the cross bar 31 will pick up all of the rack arms and return them to their initial positions without rotation of the digit wheels of

the totalizer. As soon as the pin 90 has passed the upper end of the arm 121, further movement of the roller 129 will further cam the lever 118 far enough to clear the nose 116 on the plate 106, whereupon the spring 132 acting on link 104 will return the key 100 to its initial inactive position and return the plate 106 to its position, shown in Fig. 7. As soon as the roller 129 clears the pawl 125, lever 118 will be rocked by its spring until flange 122 again engages the cam edge 115 of plate 106.

As the shaft 4 is completing its cycle of movement, the roller 129 rocks the lever 144 as before, which again may operate the key release bail 70, which again may operate the key 100, and the arm 88, Fig. 10, engages the pin 87, and rocks lever 84 to restore pin 90 to its former position in front of abutment 96 on latch 93 and carry the totalizers downwardly into driving engagement with the rack members. Thus, the totalizer digit wheels have been restored to zero positions and the machine is ready for another addition or subtraction operation.

To cause a repeat operation, the operator merely shifts the repeat key or lever 136 rearwardly, sets up the item or number in the keyboard and operates the crank arm 5 on main shaft 4, the desired number of times to enter that item in the totalizer as desired, and then the repeat key 136 is rocked back into its normal position.

It will be understood that various changes in the details and arrangements of parts, which have been herein described and illustrated in order to explain the nature of the invention, may be made by those skilled in the art within the principle and scope of the invention as expressed in the appended claims.

I claim as my invention:

1. In a calculating machine, a keyboard unit having operable keys in which numbers corresponding to the items of the calculation are to be set up in succession by selective operation of said keys; a totalizer; means mounting said unit for bodily movement between two positions; means cooperating with the keys of said keyboard and said totalizer for entering the amounts of successive numbers set up on said keyboard in said totalizer according to one type of calculation when said keyboard is in one of said positions, and for entering the amounts of successive numbers set up on said keyboard in said totalizer according to another type of calculation when said keyboard is in the other of its said positions; said keyboard having means to latch all operated keys in effective position; means yieldingly urging said keyboard into said one position; a latch device for releasably securing said keyboard in said other of its positions; said keyboard having a key release member which when operated will unlatch all operated keys of said keyboard; means operated by the key release member for operating the latch to release the keyboard for movement into said one position; means operated automatically at each calculating operation after all operated keys have performed their function for operating said key release member, to release all operated keys and to release the keyboard for return to said one position if displaced therefrom; a total key; a control element manually operable into one position by said total key; and means operable by said control element, when the latter is moved into said one position, to operate said key release member to release any operated keys and to release the keyboard for movement into said one position if displaced therefrom.

2. In a calculating machine, a frame; a totalizer having a plurality of individual digit wheels disposed side by side; a plurality of stop bar units one for each of the digit wheels disposed side by side; means interacting between each bar unit and its related digit wheel for operating the latter in a rotary direction an extent proportional to the extent of movement of that bar unit, each bar unit having two rows of abutments with the rows running in the direction of movement of that bar unit; a keyboard having a plurality of individually operable keys in which numbers corresponding to the items of the calculation may be set up in succession by selective operation of said keys, said keys having stop means which are effective when the keys are operated and which are selectively engageable with one row or the other of the abutments on said stop bar units, for determining the extent of movement of the stop bar units according to the particular key operated, the extent of movement permitted by one row of abutments of each unit representing the complement of that permitted by the abutments of the other row of the same unit; means for mounting the keyboard for shifting movement on said frame to bring the stop means on the operated keys in alignment with either row of abutments; means normally urging the keyboard to a position in which the cooperation of the stop means and the abutments allows the stop bar units to move extents corresponding to the value of the keys operated; subtraction means for shifting the keyboard from its normal position to a position in which the cooperation of the stop means and the abutments allows the stop bar units to move extents corresponding to the complement of the keys operated; a latch pivotally mounted on said frame and yieldably urged into engagement with a portion of said keyboard for holding said keyboard in its shifted position; means yieldingly urging the stop bar units in a direction to carry the abutments toward said stop means; means for positively returning all of said stop bar units to corresponding initial positions; and means operated at the end of each calculating operation after all of said stop bar units have been returned to their initial positions for releasing said latch and allowing said keyboard to be returned to its normal position under the influence of said urging means.

3. In a calculating machine, the combination of a main shaft; a plurality of digit wheels arranged side by side; a plurality of arms, one for each digit wheel, mounted for independent oscillation about a common support; a plurality of links arranged side by side and extending in the same direction from said arms, one link being provided for each arm and having one end pivotally connected thereto, and also having thereon a row of abutments spaced apart along the length of the link; means supporting the other ends of said links for endwise movement when they are moved with the arms; a member pivotally mounted intermediate its ends on each link and disposed side by side therewith, each of said members also having a row of abutments spaced apart therealong in the direction of the length of the link to which it is connected, said link supporting means also slidingly supporting the members adjacent said other ends of the links; key-controlled means for disposing stops in the path of the abutments of either row selectively to determine the extent of movement of each arm by the engagement of the stop means with an abut-

ment on either the link or the member pivoted thereon; means yieldingly urging said links, members, and arms in a direction to move the abutments into engagement with the stops; means operable by the shaft for positively returning the links, the members, and the arms from their moved positions; and means to couple the arms to the digit wheels to enable the movement of the arms in one of said directions to be transferred to the digit wheels.

4. In a calculating machine having a main shaft oscillatable through a given cycle, the combination of a keyboard; a plurality of rack members; spring-urged means connected to the rack members and cooperable with the keyboard during the first half of said cycle to enable the rack members to be displaced selected distances according to the keys which are depressed; means operated by the main shaft for restoring the rack members from their displaced positions during the second half of said cycle; a totalizer having a plurality of digit wheels, one for each rack member and mounted for shifting movement of its wheels into and out of engagement with the rack members; shifting means to impart shifting movement to the totalizer; a yieldable means cooperating with the shifting means and tending to shift the totalizer out of engagement with the rack members; means on the main shaft for operating the shifting means to shift the totalizer into engagement with the rack members at the end of the cycle of operation of the shaft; a pin on the shifting means; a latch biased to engage said pin and operable to engage said pin, when the totalizer is in engagement with the rack members, to retain the totalizer in this position; means operable by the main shaft for moving the latch out of latching engagement with the pin at the end of a cycle of operation and for maintaining the latch out of latching engagement in the beginning of a cycle until the totalizer has been shifted out of engagement with the rack members during their setting under control of the keyboard and the pin has been moved out of latching relation with the latch; and means operated by the main shaft for moving the pin at approximately the end of the first half of the cycle of operation of the shaft, to restore the pin into a position to be retained by the latch and to operate the shifting means to shift the totalizer into engagement with the rack members to be operated thereby during the return movement of the rack members, said latch retaining the totalizer in engagement with the rack members until the means on the shaft has become effective, whereby the totalizer is retained in engagement with the rack members until the end of the cycle of operation of the main shaft.

5. In a calculating machine which is operable to perform amount-entering and total-clearing operations, the combination of a totalizer having a plurality of digit wheels, said totalizer being mounted for bodily movement; a rack member for each digit wheel; means to shift the totalizer bodily to engage and disengage the digit wheels and the rack members; a keyboard; spring-urged means connected to the rack members and enabling the rack members to be set under control of the keyboard in amount-entering operations and under control of the totalizer in total-clearing operations; a main shaft oscillatable through a given cycle; means yieldingly urging the shifting means to move the totalizer out of engagement with the rack members; means on the shaft for operating the shifting means to

move the totalizer into engagement with the rack members near the end of a cycle of operation of the shaft and for freeing the totalizer for disengaging movement during the initial part of a cycle of operation to allow the totalizer to be disengaged from the rack during the first half of an amount-entering operation; a pin on the shifting means; a latch biased to engage said pin and operable to engage said pin, when the totalizer is in engagement with the rack members, to retain the totalizer in this position; means operated by the main shaft for operating the shifting means at approximately the end of the first half of the cycle of operation of the shaft, to engage the totalizer with the rack members and to place the pin in a position to be engaged by the latch to retain the totalizer in engagement with the rack members during the second half of an amount-entering operation; means operable by the main shaft for moving the latch out of pinning position at the end of a cycle of operation of the shaft and to retain the latch in this position until the pin has had time to move, during the initial part of a succeeding operation, to a position where said latch is ineffective thereon; a total key; means operated by the total key for holding said latch from engagement with said pin; a normally ineffective retaining member rendered effective by the total key, for engaging the pin to retain the totalizer in engagement with the rack members during the first half of a total-clearing operation; and means operable by means on the main shaft for returning the normally ineffective retaining member from effective position, to release the pin near the beginning of the second half of a cycle of operation of the main shaft to allow the totalizer to be disengaged from the rack members during the second half of a total-clearing operation and for releasing the holding means to restore the latch to the control of the means on the main shaft.

6. In a calculating machine which is operable to perform amount-entering and total-clearing operations, the combination of a totalizer having a plurality of digit wheels, said totalizer being mounted for bodily movement; a rack member for each digit wheel; means to shift the totalizer bodily to engage and disengage the digit wheels and the rack members; a keyboard; spring-urged means connected to the rack members and enabling the rack members to be set under control of the keyboard in amount-entering operations and under control of the totalizer in total-clearing operations; a main shaft oscillatable through a fixed cycle; means yieldingly urging the shifting means to move the totalizer out of engagement with the rack members; means on the shaft for operating the shifting means to move the totalizer into engagement with the rack members near the end of a cycle of operation of the shaft and for freeing the totalizer for disengaging movement during the initial part of a cycle of operation to allow the totalizer to be disengaged from the racks during the first half of an amount-entering operation; a pin on the shifting means; a latch biased to engage said pin and operable to engage said pin, when the totalizer is in engagement with the rack members, to retain the totalizer in this position; means operated by the main shaft for operating the shifting means at approximately the end of the first half of the cycle of operation of the shaft, to engage the totalizer with the rack members and to place the pin in a position to be engaged by the latch to retain the totalizer in engagement with the

rack members during the second half of an amount-entering operation; means operable by the main shaft for moving the latch out of pin-engaging position at the end of a cycle of operation of the shaft and to retain the latch in this position until the pin has had time to move, during the initial part of a succeeding operation, to a position where said latch is ineffective thereon; a total key yieldingly urged to inactive position but movable into a position to cause a totalizer-clearing operation; means operated by the total key, when the key is moved to position to cause a clearing operation, for holding the latch from latching engagement with said pin; a normally ineffective retaining member which, when effective, engages the pin to retain the totalizer in engagement with the rack members during the first half of a total-clearing operation; a key latch rendered operable by the operation of the total key and effective to retain the total key in moved position, said key latch, when effective to latch the total key, also being operable to render the normally ineffective retaining member effective to engage the pin and retain the totalizer engaged with the rack members during the first half of a clearing operation; and means operable by means on the main shaft for releasing the key latch near the beginning of the second half of a cycle of operation of the main shaft to restore the retaining member to its normally ineffective position to allow the totalizer to be disengaged from the rack members during the second half of a clearing operation and to allow the total key to return to its inactive position and restore the latch to the control of the means on the main shaft.

7. In a calculating machine, the combination of a totalizer having a plurality of digit wheels, said totalizer being mounted for bodily movement between two positions; shifting means for shifting the totalizer to either of said positions; a plurality of rack members with which the digit wheels have individual driving engagement only when the totalizer is in one of said positions; means yieldingly urging the shifting means to move the totalizer into disengaging position; a main shaft oscillatable back and forth in a cycle; means controlled by said keyboard and rendered effective by said shaft for causing movements of said rack members in opposite directions, which rack members can drive the totalizer wheels when they are engaged therewith; a pin on the shifting means; a latch yieldingly urged into engagement with said pin to retain the totalizer in engaged position; means operable with said shaft for operating the shifting means to move the totalizer into engaging position against the action of said urging means near the end of a cycle of operation of the shaft and to release the shifting means to the action of the urging means at the beginning of a cycle of operation of the shaft to allow the totalizer to be disengaged from the rack members during the first half of the cycle of operation of the shaft; means also operable by the shaft for operating the shifting means to move the totalizer into engaging position at approximately the end of the first half of the cycle of operation of the shaft; said latch being effective to engage the pin, when the shifting means is operated near the end of the first half of the cycle of operation of the shaft, to retain the totalizer in engagement with the rack members during the second half of the cycle of operation of the shaft; and means operable with the shaft for moving said latch into pin-releasing

position near the end of the second half of the cycle of operation of the shaft and for holding the latch in pin-releasing position until the pin has moved, during the initial part of a succeeding operation, to a position where said latch is ineffective thereon.

8. In a calculating machine which is operable to perform amount-entering and total-clearing operations, the combination of a main operating shaft oscillatable through a fixed cycle; a totalizer having a plurality of digit wheels, said totalizer being mounted for bodily movement between two positions; shifting means for shifting the totalizer to either of said positions; a plurality of rack members with which the digit wheels have individual driving engagement only when the totalizer is in one of said positions; a keyboard; a spring-urged means connected to the rack members and rendered effective by the main shaft to enable the rack members to be set under control of the keyboard in amount-entering operations and under control of the totalizer in total-clearing operations; means yieldingly urging the shifting means to move the totalizer into disengaging position; means operable with said shaft for operating the shifting means to move the totalizer into engaging position, against the action of said urging means, near the end of a cycle of operation of the shaft and to release the shifting means to the action of the urging means at the beginning of a cycle of operation of the shaft to allow the totalizer to be disengaged from the rack members during the first half of an amount-entering operation; means also operable by the shaft for operating the shifting means to move the totalizer into engaging position at approximately the end of the first half of the cycle of operation of the shaft; said latch being effective to engage the pin, when the shifting means is operated near the end of the first half of the cycle of operation of the shaft, to retain the totalizer in engagement with the rack members during the second half of an amount-entering operation; means operable with the shaft for moving the latch into pin-releasing position near the end of a cycle of operation of the shaft and for retaining the latch in this position until the pin has moved, during the initial part of a succeeding amount-entering operation, to a position where said latch is ineffective thereon; a total key; blocking means rendered operable by the total key to engage said pin and retain the totalizer in engagement with the rack members during the first half of a total-clearing operation; means operated by the total key for retaining the latch out of latching engagement with the pin during a total-clearing operation; and means operable at approximately the beginning of the second half of the cycle of operation of the shaft for removing the blocking means from engagement with the pin to allow the spring-urged means to operate the shifting means to move the totalizer out of engagement with the rack members during the second half of a total-clearing operation.
9. In a calculating machine which is operable to perform amount-entering and total-clearing operations, the combination of a main operating shaft oscillatable through a fixed cycle; a totalizer having a plurality of digit wheels, said totalizer being mounted for bodily movement between two positions; shifting means for shifting the totalizer to either of said positions; a plurality of rack members with which the digit wheels have individual driving engagement only

when the totalizer is in one of said positions; a keyboard; spring-urged means connected to the rack members and rendered effective by the main shaft to enable the rack members to be set under control of the keyboard in amount-entering operations and under control of the totalizer in total-clearing operations; means yieldingly urging the shifting means to move the totalizer into disengaging position; means operable with said shaft for operating the shifting means to move the totalizer into engaging position, against the action of said urging means, near the end of a cycle of operation of the shaft and to release the shifting means to the action of the urging means at the beginning of a cycle of operation of the shaft to allow the totalizer to be disengaged from the rack members during the first half of an amount-entering operation; means also operable by the shaft for operating the shifting means to move the totalizer into engaging position at approximately the end of the first half of the cycle of operation of the shaft; said latch being effective to engage the pin, when the shifting means is operated near the end of the first half of the cycle of operation of the shaft, to retain the totalizer in engagement with the rack members during the second half of an amount-entering operation; means operable with the shaft for moving the latch into pin-releasing position near the end of a cycle of operation of the shaft and for retaining the latch in this position until the pin has moved, during the initial part of a succeeding amount-entering operation, to a position where said latch is ineffective thereon; a total key yieldingly urged to ineffective position and movable to an effective position to cause a total-clearing operation to take place; key-retaining means for retaining the key in effective position; blocking means controlled by the key retaining means and movable to engage the pin, when the retaining means latches the key in effective position, to maintain the totalizer in engagement with the rack members during the first half of a total-clearing operation; means operated by the total key for holding the latch out of engagement with the pin; and releasing means on the shaft for operating the key-retaining means near the beginning of the second half of a cycle of operation of the shaft, to move the blocking means out of engagement with the pin and thereafter to release the total key to restore the latch to the control of the means on the shaft, whereby the latch is ineffective to retain the totalizer in engagement with the rack members and the totalizer moves out of engagement with the rack members during the second half of a total-clearing operation.

10. In a device of the class described, the combination of a row of value-representing key-operated stop members which are normally in an ineffective position but which are moved to an effective position when operated; a differentially movable means having side by side thereon two rows of abutments, one row of abutments being so spaced along the differentially movable means in the direction of its movement that cooperation of an abutment of this row with an operated stop member controls the movement of the differentially movable means to an extent representing the value of the stop member, and the other row of abutments being so spaced along the differentially movable means in the direction of its movement that cooperation of an abutment of this row with an operated stop member controls the movement of the differentially movable

means to an extent representing the complement of the value of the operated stop member, said other row of abutments being capable of limited movement relative to said one row of abutments; means for causing said other row of abutments to be moved relatively to said one row of abutments during movement of said differentially movable means; means for mounting the stop members for movement relative to the differentially movable means, said mounting means supporting the stop members normally for performing addition, with the stop members in alignment with the abutments which control the extents of movement of the differentially movable means to represent the values of the stop members; subtraction control means for shifting the mounting means for the stop members to bring the stop members into alignment with the other row of abutments to enable the same set of stop members to control the extents of movement of the differentially movable means to represent the complement of the value of the stop members; and means to restore the mounting means to normal position automatically at the end of a subtraction operation.

11. In a device of the class described, the combination of a row of value-representing key-operated stop members which are normally in an ineffective position but which are moved to an effective position when operated; a differentially movable means having side by side thereon two rows of abutments, one row of abutments being so spaced along the differentially movable means in the direction of its movement that cooperation of an abutment of this row with an operated stop member controls the movement of the differentially movable means to an extent which represents the value of the stop member, and the other row of abutments being so spaced along the differentially movable means in the direction of its movement that cooperation of an abutment of this row with an operated stop member controls the movement of the differentially movable means to an extent representing the complement of the value of the operated stop member, said other row of abutments being capable of limited movement relative to said one row of abutments; means for causing said other row of abutments to be moved relatively to said one row of abutments during movement of said differentially movable means; means for mounting the stop members for movement relative to the differentially movable means; means yieldingly positioning the mounting means normally in a position to bring the stop members in alignment with the abutments which control the extents of movement of the differentially movable means to represent the values of the stop members, for performing addition; subtraction control means for shifting the mounting means to bring the stop members into alignment with the other row of abutments to enable the same set of stop members to control the extent of movement of the differentially movable means to represent the complement of the value of the stop members for performing subtraction; means for latching the mounting means in the position to which it is set for subtraction; and means to release the latching means automatically at the end of a subtraction operation to allow the mounting means to return the stop members to their normal, addition position.

12. In a device of the class described, the combination of a row of digit-representing key-operated stop members which are normally in an ineffective position but which are moved to an ef-

fective position when operated; a differentially operated member formed with a set of abutments which are cooperable with operated stop members to control the movement of the differentially operable member different extents from a home position to represent the values of the operated stop members; an auxiliary member carried by the differentially operable member and capable of limited movement relative thereto, said auxiliary member being formed with a set of abutments which when cooperable with the operated stop members can control the movement of the differentially operable member different extents from a home position to represent values which bear a predetermined relation to the values of the operated stop members; means for mounting the stop members for shifting movements relative to the sets of abutments; means to shift the stop members into alinement with either set of abutments to enable the operated stop members to control the movement of the differentially operable member to represent the values of the stop members or to represent values which bear a predetermined relation to the values of the stop members; means urging the auxiliary member to move relatively to the differentially operable member to bring certain of the abutments thereon out of cooperative relation with the operated stop members in the home position of the differentially operable member and the auxiliary member; and means operable after a predetermined extent of movement of the differentially operable member and the auxiliary member, to cause the auxiliary member to move relatively to the differentially operable member and place all the abutments thereon in cooperative relation with the operated stop members so that the stop members, if in alinement therewith, can control the extent of movement of the differentially operable member.

13. In a device of the class described, the combination of a row of digit-representing key-operated stop members which are normally in an ineffective position but which are moved to an effective position when operated; a differentially operable member having thereon two sets of abutments, one set of abutments being cooperable with operated stop members of the row to control the movement of the differentially operable member from a home position different extents representing the values of the stop member and the other set of abutments being cooperable with the same operated stop members of the row to control the movements of said differentially operable member from said home position different extents representing values which bear a predetermined relation to the values of the stop members; said differential member being formed to provide one of said sets of abutments and having pivoted thereon an auxiliary member formed with the other set of abutments; means to mount the stop members for shifting movement relative to the sets of abutments; means to shift the stop members into alinement with either set of abutments to enable the operated stop members to control the movement of the differentially operable member to represent the values of the stop members or to represent values which bear a predetermined relation to the values of the operated stop members; means urging the auxiliary member about its pivot to move certain of the abutments thereon out of cooperative relation with the operated stop members in the home position of the differentially operable member; and means operable after a predetermined extent of move-

ment of the differentially operable member and therewith the auxiliary member, to cause the auxiliary member to rock about its pivot and place all the abutments in cooperative relation with the operated stop members so that the stop members, if in alinement with the abutments on the auxiliary member, can control the extent of movement of the differentially operable member.

14. In a device of the class described, the combination of a row of digit-representing key-operated stop members which are normally in an ineffective position but which are moved to an effective position when operated; a differentially operable member formed with a set of abutments which are cooperable with operated stop members to control the movement of the differentially operable member extents representing the values of the operated stop members; an auxiliary member pivoted to the differentially operable member and having a set of abutments which when cooperable with the operated stop members can control the movement of the differentially operable member extents representing values which are complements of the values of the operated stop members; means for mounting the stop members for shifting movements relative to the sets of abutments; means to shift the stop members into alinement with either set of abutments to enable the operated stop members to control the movement of the differentially operable member to represent the values of the stop members or to represent values which are the complements of the values of the stop members; means urging the auxiliary member about its pivot to move certain of the abutments thereon out of cooperative relation with the operated stop members in the home position of the auxiliary member; and means operable after a predetermined extent of movement of the auxiliary member, to cause the auxiliary member to rock about its pivot and place all the abutments in cooperative relation with the operated stop members so that the stop members, if in alinement therewith, can control the extent of movement of the differentially operable member.

15. In a calculating machine having a main shaft oscillated back and forth in a cycle, the combination of a totalizer having a plurality of digit wheels; a corresponding plurality of rack members; a keyboard; means controlled by said keyboard and rendered effective by said main shaft for causing movements of said rack members in opposite directions; shifting means to cause relative movement between the digit wheels and the rack members to engage the wheels and the rack members so that the wheels can be driven by the rack members, and to cause disengagement between the wheels and the rack members to prevent such driving action; means yieldingly urging the shifting means to cause disengagement between the wheels and the rack members; means operable with the shaft for operating the shifting means, against the action of the urging means, to cause engagement between the wheels and the rack members near the end of a cycle of operation of the shaft and to release the shifting means to the action of the urging means at the beginning of a cycle of operation of the shaft to cause the disengagement between the wheels and the rack members during the first half of the cycle of operation of the shaft; a projection on the shifting means; a latch cooperable with the projection to retain the shifting means in position to cause engagement between the digit wheels and the rack

members; means also operable by the main shaft for operating the shifting means to cause engagement between said digit wheels and the rack members at the end of the first half of a cycle of operation of the shaft; said latch being effective to engage the projection, when the shifting means is operated near the end of the first half of the cycle of operation of the shaft, to maintain the engagement between the wheels and the rack members during the second half of the cycle of operation of the shaft; and means operable with the shaft for moving said latch out of engagement with the projection near the end of the second half of the cycle of operation of the shaft and for holding the latch in this position until the projection has moved, during the initial part of a succeeding operation, to a position where said latch is ineffective thereon.

16. In a calculating machine which is operable to perform amount-entering and total-clearing operations, the combination of a main shaft operable through a fixed cycle; a totalizer having a plurality of digit wheels; a corresponding plurality of rack members; shifting means to cause relative movement between the digit wheels and the rack members to engage the wheels and the rack members so that the wheels can be driven by the rack members, and to cause disengagement between the wheels and the rack members to prevent such driving action; a keyboard; spring-urged means connected to the rack members and enabling the rack members to be set under control of the keyboard in amount-entering operations and under control of the totalizer in total-clearing operations; means operated by the main shaft for positively restoring the rack members from their set positions; means yielding-urging the shifting means to cause disengagement between the wheels and the rack members; means operable with the shaft for operating the shifting means, against the action of the urging means, to cause engagement between the wheels and the rack members near the end of a cycle of operation of the shaft and to release the shifting means to the action of the urging means at the beginning of a cycle of operation of the shaft to cause disengagement between the wheels and the rack members during the first half of an amount-entering operation; a projection on the shifting means; a latch cooperable with the projection to retain the shifting means in position to cause engagement between the digit wheels and the rack members; means also operable by the main shaft for operating the shifting means to cause engagement between the digit wheels and the rack members at the end of the first half of a cycle of operation of the shaft and to place the projection in position to be engaged by the latch to maintain the engagement between the digit wheels and the rack members during the second half of an amount-entering operation; means operable by the main shaft for moving the latch out of cooperating relation with the projection near the end of a cycle of operation of the shaft and to retain the latch in this moved position until the shifting means has operated in the initial part of a succeeding amount-entering operation to move the projection out of cooperation with the latch; a total key; means operated by the total key for holding the latch out of cooperation with the projection; blocking means rendered operable by the total key to engage the projection and retain the digit wheels and the rack members in engagement during the first half of a total-clearing operation; and means

operated by the main shaft at the beginning of the second half of the cycle of operation of the shaft, for removing the blocking means from engagement with the projection to cause disengagement between the digit wheels and the rack members during the second half of a total-clearing operation, and for restoring the latch to the control of the means on the shaft.

17. In a calculating machine having a main shaft oscillatable through a given cycle, the combination of a keyboard; a plurality of rack members; yieldable means connected to the rack members and cooperable with the keyboard during the first half of said cycle to enable the rack members to be displaced selected distances according to the keys which are depressed; means operated by the main shaft for restoring the racks from their displaced positions during the second half of said cycle; a totalizer having a plurality of digit wheels, one for each rack member; means for mounting said totalizer for shifting movement of its wheels into and out of engagement with the rack members; mechanism to move the mounting means to impart shifting movement to the totalizer; a yieldable means cooperating with the moving mechanism and tending to shift the totalizer out of engagement with the rack members; means on the main shaft for operating the moving mechanism to shift the totalizer into engagement with the rack members at the end of the cycle of operation of the shaft; a pin on the moving mechanism; a latch biased to engage said pin and operable to engage said pin, when the totalizer is in engagement with the rack members, to retain the totalizer in this position; means operable by the main shaft for moving the latch out of latching engagement with the pin at the end of a cycle of operation and for maintaining the latch out of latching engagement in the beginning of a cycle until the totalizer has been shifted out of engagement with the rack members during their setting under control of the keyboard and the pin has been moved out of latching relation with the latch; and means operated by the main shaft for moving the pin at approximately the end of the first half of the cycle of operation of the shaft, to restore the pin into latching engagement with the latch and to operate the moving mechanism to shift the totalizer into engagement with the rack members to be operated thereby during the return movement of the rack members, said latch retaining the totalizer in engagement with the rack members until the means on the shaft has become effective, whereby the totalizer is retained in engagement with the rack members until the end of the cycle of operation of the main shaft.

18. A calculating machine comprising a frame; a keyboard having a plurality of rows of individually operable keys which may be operated to set up given amounts; means for mounting said keyboard for sidewise movement relative to said frame; a totalizer; a differentially operable means cooperating with the operated keys of said keyboard, said last-named means comprising a plurality of differential members each provided with a plurality of abutments for cooperating with the operated keys, and an auxiliary differential member carried by each of said differential members and capable of limited movement relative thereto, said auxiliary differential members each being provided with a series of abutments arranged complementally to the abutments on said differential members; and means for enabling said keyboard to be positioned with its keys

33

in cooperable relationship with the abutments on said differential members for the purpose of causing amounts to be added into said totalizer, or to be positioned with its keys in cooperable relationship with the abutments on said auxiliary differential members for the purpose of causing the amount set up on said keys to be subtracted from said totalizer.

19. A calculating machine comprising a frame; a keyboard having a plurality of rows of individually operable keys for receiving numerical entries; means for mounting said keyboard for sidewise movement relative to said frame; a totalizer; a differentially operable means cooperating with the operated keys of said keyboard, said last-named means comprising a plurality of differential members each provided with a plurality of abutments for cooperating with the operated keys, and an auxiliary differential member carried by each of said differential members and capable of limited movement relative thereto, said auxiliary differential members each being provided with a series of abutments arranged complementally to the abutments on said differential members; means for yieldably urging said keyboard into one position in which the keys are in a position to cooperate with the abutments on said differential members so as to cause the amount entered on the keyboard to be added into the totalizer; means for enabling said keyboard to be moved into a second position in which its keys are in a position to cooperate with the abutments on said auxiliary differential members so as to cause the complement of any amount entered on said keys to be subtracted from said totalizer; means for moving said auxiliary differential members relatively to said differential members during amount-entering operations; means for retaining said keyboard in said second position against the bias of said urging means; and means for releasing said retaining means at the end of each amount-entering operation so as to enable the keyboard to return to said first position if displaced therefrom.

20. A machine of the class described comprising a row of individually operable amount keys, each of said keys having a stop portion adapted to be moved into effective position when the key is operated; a differential control unit provided with two sets of abutments, one set of abutments being cooperable with the stop portion of any operated key of said row to control the movement of said differential control unit in one type of calculation, and the other set of abutments being relatively movable with respect to the first-mentioned set of abutments and arranged in a different manner on said unit from the first-mentioned set so as to control the movement of said differential control unit in a different manner in another type of calculation; means to shift the stop portions of said keys out of cooperable relationship with the first-mentioned set of abutments and into cooperable relationship with the second set of abutments; and means to cause the second-mentioned set of abutments to be moved relatively to said first-mentioned set of abutments during movement of said differential control unit.

21. A device of the class described comprising a row of individually operable keys each having a stop portion adapted to be moved into operative position when said key is operated; a differentially operable means provided with two sets of abutments, one set of abutments being cooperable with the stop portions of operated keys

34

of said row to control the movement of said differentially operable means to an extent representative of the value of the operated key, and the other set of abutments being cooperable with the stop portions of said keys to control the movement of said differentially operable means to an extent representative of values which bear a predetermined relationship to the values of the operated keys, said other set of abutments also being capable of limited movement relative to said one set of abutments; means for causing said other set of abutments to be moved relatively to said one set during movement of said differentially operable means; means for supporting said row of keys and their associated stop portions in alignment with one of said sets of abutments; means for enabling said supporting means to be shifted to bring the stop portions of said keys into alignment with said other set of abutments; and means for automatically restoring said supporting means to its normal position, in which said stop portions are in cooperative relationship with said one set of abutments at the end of each amount-entering operation.

22. In a device of the class described, the combination of a row of individually operable keys, each having a stop portion adapted to be moved into operative position when the key is operated; a differentially operable means provided with two adjacent rows of abutments, one row of abutments being so spaced along the differentially operable means in the direction of its movement that the cooperation of an abutment of this row with the stop portion of an operated key controls the movement of the differentially operable means to an extent representative of the value of the operated key, and the other row of abutments being so spaced along the differentially operable means in the direction of its movement that the cooperation of an abutment of this row with the stop portion of an operated key controls the movement of the differentially operable means to an extent representative of the complement of the value of the operated key, said other row of abutments being relatively movable with respect to said one row of abutments; means for causing said other row of abutments to be moved relatively to said one row of abutments during movement of said differentially operable member; means for mounting said row of keys and their associated stop portions for movement relative to said abutments, said mounting means normally supporting said keys in a position to perform addition, with the stop portions in alignment with said one set of abutments; and subtraction control means for shifting the keys to bring their stop portions into alignment with said other row of abutments so as to enable the same stop portions to control the extent of movement of the differentially operable means to represent the complement of the value on the keys for performing subtraction.

23. A device of the class described comprising a row of individually operable keys each having a stop portion adapted to be moved into effective position when the key is operated; a differential control member provided with two sets of abutments, one of said sets being arranged in a different manner on said differential control unit from the other of said sets and being capable of limited rotational movement relative thereto; means for enabling either of said sets of abutments to be brought into cooperative relationship with the stop portions of said keys; and means for causing said one set of abutments to be moved

relatively to said other set during movement of said differential control unit.

24. A calculating machine comprising a keyboard provided with a plurality of amount keys; a totalizer; means for mounting said keyboard for bodily movement between two positions; means cooperating with the keys of said keyboard for entering amounts set up on said keyboard into said totalizer according to one type of calculation when said keyboard is in one of said positions; and for entering amounts set up on said keyboard into said totalizer according to another type of calculation when said keyboard is in the other of said positions; means yieldably urging said keyboard into said one position; a latch device for releasably securing said keyboard in said other position; a total key; and means operated by said total key when the latter is actuated to disable said latch device and release the keyboard for movement into said one position if displaced therefrom.

25. A calculating machine comprising a keyboard having a plurality of rows of depressible keys, each of said keys having a stop portion adapted to be brought into effective position when said key is depressed; a stop bar located beneath each row of keys and positioned at an angle with respect to said keyboard, each of said bars having a plurality of abutments adapted to cooperate with said key stops, the abutments on said bars being spaced somewhat closer together than said key stops so that there is an overlapping relationship between certain of the key stops and the abutments on said bars; means for imparting a reciprocating motion to said stop bars so that the angle of said bars relative to the keyboard varies during the forward movement of said stop bars until said bars have reached a forward maximum position so as to prevent the overlapping key stops from contacting the wrong abutments; an auxiliary complementary stop bar pivotally mounted on the side of each of said stop bars and having abutments thereon arranged complementally to the abutments on said stop bars; means by which the keys may be caused to cooperate selectively with the group of stops on either of the stop bars; and means for causing each of said auxiliary complementary stop bars to be rotated about its pivot during the forward movement of the stop bars so as to prevent those key stops which bear an overlapping relationship with respect to the abutments on said auxiliary stop bars from cooperating with the wrong abutments.

26. A calculating machine comprising a keyboard having a plurality of rows of depressible keys, each of said keys having a stop portion adapted to be moved to effective position when said key is depressed; a stop bar located beneath each row of keys having a plurality of abutments adapted to cooperate with said key stops, the abutments on the stop bars being spaced some-

what closer together than the key stops, thereby causing an overlapping relationship between certain of the key stops and their related abutments; means for supporting said stop bars for longitudinal, reciprocatory motion, said means comprising a comb plate for supporting the forward ends of said stop bars, a shaft, a plurality of arms mounted for oscillatory movement on said shaft, and means for pivotally connecting the rear end

5 of each stop bar to one of said arms, said arms being positioned slightly to the rear of their point of highest throw so that as said bars move forward their rear ends will be raised toward the keyboard so as to be in a position to cooperate 10 with any depressed key stops; an auxiliary stop bar pivotally mounted on the side of each of the stop bars and having thereon abutments arranged complementally to the abutments on said stop bars; means by which the keys may be caused to 15 cooperate selectively with the group of abutments on either of the stop bars; and a camming portion formed on the lower edge of the forward end of each of said auxiliary stop bars which is adapted to cooperate with said comb plate during 20 the forward movement of said stop bars and cause said auxiliary stop bars to be rotated about their pivots so as to bring their forward ends into 25 engaging relationship with said key stops after those abutments bearing an overlapping relationship with respect to certain of the key stops 30 have passed beyond the latter stops and are no longer in a position to be stopped by them.

27. The invention as defined in claim 26, wherein means is provided for yieldably urging the 35 lower edge of said auxiliary stop bars into engagement with said comb plate to thereby maintain the forward ends of said auxiliary stop bars in their lowered positions until they are cammed upwardly by the camming portions formed thereon during the forward movement of said stop bars.
